UNITED STATES PATENT OFFICE

THOMAS B. SCHMIDT, OF HARRISBURG, PENNSYLVANIA

DESIGN FOR A DISPENSING CABINET

Application filed April 12, 1930. Serial No. 35,238. Term of patent 14 years.

To all whom it may concern:

Be it known that I, THOMAS B. SCHMIDT, a citizen of the United States of America, and resident of the city of Harrisburg, county of Dauphin, and State of Pennsylvania, have invented a new, original, and ornamental Design for Dispensing Cabinets, of which the following is a specification, reference being had to the accompanying drawing, forming part thereof.

The figure is a view in perspective of a dispensing cabinet, showing my new design.

I claim:

The ornamental design for a dispensing cabinet as shown.

THOMAS B. SCHMIDT.
